CLOSURE FOR LIQUID CONTAINERS

Frederick John Trevallon Barnes, Brisbane,
Queensland, AustraliaApplication June 22, 1935, Serial No. 27,987
In Great Britain December 14, 1933

9 Claims. (Cl. 217—110)

This invention relates to means for use in filling or emptying liquid containers or for automatically sealing them under pressure and resealing them under pressure, or for sterilizing containers, and an object of the invention is to provide an arrangement which may be employed for any of these purposes.

According to the present invention a valve for closing a bushing in a liquid container comprises a head to engage the inner end of the bushing and thereby seal it and a projection or projections from the head to engage the bushing whereby the valve may be supported by the bushing, and to engage the end of a stem inserted through the bushing (for example, the stem of an extractor), whereby the valve may be supported by the stem. The purpose of this arrangement is that when the stem is passed through the bushing and down into the container the valve is removed from its seat but remains supported on the stem. When the stem is withdrawn through the bushing, the valve is returned to its position in engagement with the bushing.

According to this invention also, in or for a container for liquids, there is provided an extractor comprising, in combination, a unit comprising two tubes one inside the other to provide a conduit between them, the outer tube having two apertures, one adapted to communicate with the inside of the container and the other with the outside thereof, a closure for said conduit at the inner end of the said unit, a removable valve member for closing the inner end of a bushing secured within the bung-hole of the container, means on the said unit for engaging and removing the valve member when the unit is inserted through the bushing, and means for again securing the valve member against the bushing, upon withdrawal of the unit.

The projection or projections aforesaid may be resilient to engage recesses in the inner wall of the bushing and in the end of the stem. Alternatively, the projection aforesaid from the head of the valve may be a tubular portion externally screw-threaded to engage screw-threads in the bushing and internally screw-threaded to engage screw-threads on the stem.

Other features of the invention will appear hereinafter.

Specific embodiments of the present invention will now be described, by way of example, with reference to the accompanying drawings, in which:—

Figure 1 is a sectional elevation of one form of extractor according to the invention.

Figure 2 is a view of the extractor stem and valve member in a different position.

Figures 3 and 4 are a sectional elevation and a sectional plan respectively of an alternative form of valve member according to the invention, Figure 4 being a section on the line 4—4 of Figure 3.

Figures 5 and 6 are an elevation and plan respectively of yet another form of the invention, Figure 6 being a section on the line 6—6 of 10 Figure 5, whilst

Figures 7, 8, and 9 are views of further modified forms of the invention.

Figure 10 shows a valve applied to a modified form of extractor.

As shown in Figures 1 and 2, a metal bush 10 is fitted to the bung-hole of a liquid container, such as a beer barrel, by a surrounding bushing 11 having a packing ring 12 and a screw-threaded annulus 13. The extractor comprises two nut members 14, 15 each having grip portions 16. The nut 14 is screw-threaded on to the bush 10 and a sleeve 17 of resilient material makes a fluid-tight joint between a collar 18 on the nut 14 and the top annular surface of the bush 10. The nut 15 is screwed into the nut 14 and engages a rubber packing ring 19.

The extractor stem comprises two concentric tubes 20, 21, one inside the other and the conduit between these tubes is closed at the bottom by an annular plug 22.

At the top of the stem the tubes engage an elbow 23 and a hole 24 in the wall of the outer tube 20 communicates with a laterally-extending bore 25 whilst the inner tube 21 is received in the vertical limb 26 of the elbow. A port 30 is formed in the outer tube 20 at a point high up in the stem when the stem is in position within the container.

A valve for closing the bushing comprises a 40 steel frusto-conical disc 47 having riveted thereto a series of upstanding prongs or tongues 50 formed with curved heads 54 to engage a groove 55 cut in the stem near its lower end. A rubber extension 49 is formed with an inwardly-directed 45 flange 65 which engages a groove in the lower end of the bush and a screw-threaded collar 66 engages the outer wall of the rubber extension at the region of the flange 65 and may be screwed down to lock the rubber in position on the bush. 50 It will be seen that the disc-portion 47 of the valve seats in a V-shaped groove in the bore of the rubber and that the bore is flared outwardly beyond this point.

The extractor is fitted to a container as fol- 55

lows. The stem is passed through the nut 14 until the tapering inner end 39 of the stem passes between the curved ends 54 of the tongues 50 and wedges them apart. Downward movement 5 of the valve is so far prevented by the engagement of the disc 47 with the groove in the rubber 49. When the stem has been moved down into the position shown in Figure 1, the curved ends 54 in the spring into engagement with the groove 55 in the 10 stem and further downward movement of the stem causes the disc 47 to expand the rubber 49 and pass downwardly out of the groove. The stem is passed down, with the valve supported on it, as shown in Figure 2, until the bottom of 15 the stem is near the bottom of the container. A fluid-tight seal between the extractor body and the stem is now obtained by tightening the nut 15 with respect to the nut 14, whereby the packing ring 19 is distorted to expand it in a radial 20 direction. An alternative form of seal is described later with reference to Figure 10.

The extractor is used for sterilizing and filling the container in a manner described later.

In the alternative construction shown in Figures 3 and 4 the valve comprises a flanged head 27 and a packing ring 31. Formed integrally with the flanged head is a series of upstanding tongues 32 and 33 of springy metal. The tongues 32 (see Figure 4) spring inwardly to engage a recess 35 in the lower end of the stem 20; the alternate tongues 33 are sprung outwardly so that they engage a shouldered recess 36 in the internal surface of the bush 10.

It will be seen that the upper end of each 35 metal tongue is formed with a barbed enlargement 37 and that the bore of the bush 10 is slightly flared outwardly at 38, for reasons explained below.

40 When the stem 20 is passed down through the bush into engagement with the valve, the lower end 39 of the stem, which is tapered, as shown, forces the tongues 32 outwardly by a wedging action until the stem reaches the position shown 45 in Figure 3 at which these four tongues spring inwardly over the enlargement 48 to engage the recess 35. Further downward movement of the stem 20 causes the remaining tongues 33 to be wedged inwardly by the action of the shoulder 50 36 in the bush, so that the stem with the eight tongues engaged in the groove 35, forces the valve 55 out of the bush. When the tongues 33 are clear of the bush they spring outwardly but the valve is retained on the stem by the remaining tongues 32.

Upon withdrawal of the stem the outwardly sprung tongues 33 enter the flared portion 38 of the bush and are forced inwardly by a wedging action so that the tongues pass up through the bush and the valve resumes the position shown in Figure 3.

In the alternative construction shown in Figures 5 and 6 the valve 41 is of rubber comprising a head portion and an upstanding tubular wall 65 42. The wall 42 is formed with a rib 43 which engages on the inside with a groove 44 in the stem 20 and on the outside with a shoulder 45 in the bush 10. This valve operates in the same way as 70 that described with reference to Figures 3 and 4 except that, instead of deflection of metal tongues, the rubber of the valve is deformed to permit it to pass out of the bush on the downward movement of the stem; on withdrawal of the 75 stem the rib 43 is compressed by the flared por-

tion 46 of the bush to allow it to pass back into the position shown in Figure 5.

An alternative form of valve is shown in Figure 7. In this construction the head 47 of the valve takes the form of a metal disc of stainless 5 steel having its lower face slightly larger than its upper face as shown. The metal disc is adapted to engage with a V-shaped groove 48 in the inner wall of a tubular rubber portion 49 engaging a groove in the bush 10.

10 The head 47 of the valve is formed with a plurality of upstanding tongues 50 adapted to engage a peripheral groove in the stem 51 of an extractor.

In this construction, when the stem 51 is inserted through the bushing 10, its lower end separates the tongues 50 until they spring into the groove in the stem as shown in Figure 7. Further downward pressure on the stem causes the head 47 of the valve to spread the rubber portion outwardly and to pass down into the container. The valve is retained on the stem 51 by engagement of the tongues 50 with the groove. When the stem is withdrawn the conical wall of the head 47 engages the outwardly flared portion 52 of the rubber portion 49 and thereby expands the rubber, permitting the metal head 47 to pass back into the position shown in Figure 7.

30 In the modified arrangement shown in Figure 8, the valve member comprises metal tongues 50, as already described with reference to Figure 1. These tongues are riveted to a thick disc-shaped base 80 having a sharp upstanding edge 81 to engage a rubber ring 82 on the bottom of the bush.

35 In the construction of Figure 9, the bush 10 has a rubber portion 69 acting as the valve seat accommodated in an enlargement at the bottom 40 of the bush and the rubber 69 is retained in the bush by a shouldered nut 70 screw-threaded on to the bush. In order to accommodate the deformation of the rubber which takes place when the metal valve head 47 is being forced out of 45 or into the rubber, the enlarged portion of the bush bore is formed with a peripheral recess 71 into which the rubber 69 can expand when deformed.

50 When the stem is in position within the container, as shown in Figure 2, the container may be sterilized by forcing a detergent liquid along the pipe 25 from whence it flows out through the port 30, in through the holes 29 in the valve and exhausts through the inner tube 21. For example, superheated steam may be used, followed 55 by carbon-dioxide or other suitable gas.

The container may be filled with liquid by connecting the vertical limb 26 of the elbow to a source of liquid supply. The liquid flows down 60 the tube 21 and through the ports 29 in the valve; meanwhile the air or gas in the container escapes through the port 30 passes up the conduit formed by the space between the two tubes and exhausts through the port 24 into the pipe 65 25. When liquid is to be drawn off from the container either the form of extractor shown in Figure 1 may be used or that shown in Figure 10, which will now be described.

70 Figure 10 shows a valve according to the invention in conjunction with an extractor, the features of which are more fully described and are claimed in my copending application Serial No. 757,584, filed 14th December 1934. This extractor comprises a lever 90 (Figure 10) rotatable about trunnions 91 and having a cam or cams 92 75

whereby the rubber ring between the extractor body and the stem may be distorted to make the seal.

The metal bush 10, in this construction, has a packing ring 60 of resilient material, such as rubber and canvas, surrounding it, and a nut 61 and washer 62 for applying pressure to the ring 60. The nut 61 has a castellated or slotted extension 63 for engagement by a tool. A rubber extension 64 engages the lower end of the bush 10 by an inwardly-directed flange 65 as in the construction of Figure 7; cooperating with this flange is a nut 66 having a depending tapering portion 67 to engage the outer surface of the rubber 64. By screwing down the nut 66 the rubber portion 64 may be locked securely in position on the bush. The remainder of the valve is similar to that already described with reference to Figures 1 and 2.

To provide a passage between the head of the valve and the end of the stem, the end of the stem may be formed with radial holes 95 as shown in Figures 3, 5, 7, and 8. In order that there shall be no risk of the metal tongues of the valve becoming engaged with these holes, the stem is preferably formed with a peripheral groove with a gradual expansion to the main part of the stem; thus, as the stem is passed into the valve, the metal tongues, if they engage the holes, are disengaged by further movement of the stem. However, the preferred arrangement is shown in Figures 1, 2, 9, and 10 in which there are no radial holes in the end of the stem but the stem is open at its lower end and spaced a short distance away from the head portion of the valve so as to leave a space 96, as shown in Figure 1. The metal tongues are an accurate fit where they engage the stem so that there is no risk of the space 96 being closed up during operation of the extractor. The space 96 may be made of such size as to act as a strainer.

I claim:—

1. A bung hole fitting for liquid containers comprising a tubular bushing for the bung hole, a disc valve member normally closing said bushing but displaceable out of said bushing by a draw off stem inserted in said bushing, resilient means for holding said valve member in a position closing said bushing, and axially extending resilient holding means on said valve member adapted to encircle a draw-off stem inserted in said bushing, said holding means having one or more detent portions projecting radially inwardly therefrom, which engage with a peripheral groove on the draw-off stem.

2. A bung hole fitting for liquid containers comprising a tubular bushing for the bung hole, a disc valve member normally closing said bushing, an annular recess within the bore of said bushing towards its inner end, axially extending resilient means on said valve member having radially outwardly directed parts for engaging in said recess to hold said valve member in a position closing said bushing, and resilient catch means on said valve member having radially inwardly directed parts for engagement with a peripheral groove on the outside of a draw-off stem inserted in said bushing.

3. A bung hole fitting for liquid containers comprising a tubular bushing for the bung hole, a disc valve member normally closing said bushing but displaceable out of said bushing by a draw off stem inserted in said bushing, axially

extending resilient catch means having radially outwardly directed parts for engagement with the bushing, and holding said valve member in a position closing said bushing, and spring catch means on said valve member having radially inwardly directed parts adapted to engage in a peripheral groove on the outside of a draw off stem inserted in said bushing.

4. A bung hole fitting for liquid containers comprising a tubular bushing for the bung hole, 10 a disc valve member normally closing said bushing but displaceable out of said bushing by a draw off stem inserted in said bushing, axially extending resilient catch means having radially outwardly directed parts for engaging said bushing and holding said valve member in a position closing said bushing, and spring fingers on said valve member having radially inwardly projecting parts adapted to engage in a peripheral groove on the outside of a draw off stem inserted 20 in said bushing.

5. A bung hole fitting for liquid containers comprising a bushing for the bung hole, a disc valve for closing said bushing, a rubber sleeve forming an extension of said bushing and having an internal groove to receive the edge of said valve and resilient holding means on said valve member for gripping a draw off stem inserted in said bushing.

6. A bung hole fitting for liquid containers comprising a bushing for the bung hole, a disc valve having a bevelled upper edge for closing said bushing, a rubber sleeve forming an extension of said bushing and having an internal V groove to receive the edge of said valve, and resilient holding means on said valve member for gripping a draw off stem inserted in said bushing.

7. A bung hole fitting for liquid containers comprising a bushing for the bung hole, a disc valve for closing said bushing, an annular recess within the bore of said bushing towards its inner end, a rubber sleeve on the upper surface of said valve having an external rib to engage in said recess to hold said valve member in a position closing said bushing, and resilient holding means on said valve member for gripping a draw off stem inserted in said bushing.

8. A bung hole fitting for liquid containers comprising a bushing for the bung hole, a disc valve for closing said bushing, an annular recess within the bore of said bushing towards its inner end, a rubber sleeve on the upper surface of said valve having an external rib to engage in said recess to hold said valve member in a position closing said bushing, and an external rib on said sleeve to engage in a peripheral recess on a draw off stem inserted in said bushing.

9. A bung hole fitting for liquid containers comprising a bushing for the bung hole, a valve member normally closing said bushing, an annular recess within the bore of said bushing towards its inner end, two sets of spring fingers on said valve member, inwardly projecting parts on the ends of one set of fingers adapted to engage in a peripheral recess on a draw off stem inserted in said bushing, and outwardly projecting parts on the ends of the other set of spring fingers adapted to engage in the annular recess in the bore of the bushing.

FREDERICK JOHN TREVALLON BARNES.
